STUD SETTER

Claude I. Hess, Detroit, Mich.

Application April 13, 1934, Serial No. 720,452

4 Claims. (Cl. 81—53)

This invention relates to automatic chucks and the like, and is particularly concerned with tools for driving and releasing threaded studs, screws and other elements of virtually any nature which require twisting during their manipulation. Directed particularly to improvement of my previous invention disclosed in United States Letters Patent No. 1,898,726, issued February 21, 1933, the present invention embraces among other important objects the simplification of such stud driving and similar devices to a degree rendering them much simpler and less expensive of construction, as well as more rugged and reliable in operation by virtue of the elimination of parts previously regarded indispensable.

Another object is to provide in a tool of the class indicated a novel semi-floating driven and clutching element which is completely encased by the driving portions and resiliently connected to those portions in such fashion as to be limitedly movable independently thereof to clutch and release the object being driven by engagement of certain parts with the object being driven, as well as by the resilient connecting means and by engagement with other parts with the work itself.

A further object is the provision of means whereby the resilient connection may be quickly and easily adjusted in tension.

Still another object is the incorporation in such devices of improved adjusting means enabling accommodation of studs and the like of variant dimensions.

Other objects and advantages will be apparent from the following description wherein reference is made to the accompanying drawing illustrating preferred embodiments of my invention, and wherein similar reference numerals designate similar parts throughout the several views.

In the drawing:

Figs. 1 and 2 are substantially diametrical longitudinal sections of a stud driver incorporating the principles of this invention, respectively showing the parts in the initial position they occupy before the stud is gripped, and in their operative position while the stud is being held and driven but shortly before the completion of that operation.

Fig. 3 is a cross section taken substantially on line 3—3 of Fig. 1 and looking in the direction of the arrows.

Figs. 4 and 5 are cross sectional views taken substantially on the lines 4—4 and 5—5 respect-

ively of Fig. 2 and looking in the direction of the arrows.

Fig. 6 is a view similar to Fig. 2 of a somewhat modified form of the invention; and

Fig. 7 is a cross section taken substantially on the line 7—7 of Fig. 6 and looking in the direction of the arrows.

Referring now to the drawing: Reference character 10 designates a driving shank, rigidly connected to a casing which is shown formed of initially separate sections 11—12 tightly secured together, as by being threadedly interfitted (at 14). The casing also serves as a driving element. The shank is also shown as a separate element threadedly secured to casing section 12, as at 16, 18, and it will be appreciated that by substituting shanks of different forms the driver may be adapted to fit holding portions of any of various rotating tools of the electric, pneumatic or other desired sort.

A torque transmitting and chuck operating cam 15 of substantially annular form having an active inner face of uniform taper axially of the cam, which is greatest in width toward the front of the tool, (left as viewed in the drawing) is keyed to the casing member 12 to rotate therewith. The keyway 17 locks the cam against turning within the casing member 12, and its position is determined by the male portion of casing section 11, which forces the front end of the cam against a shoulder in casing section 12 and the interposed shims 18. The longitudinal positioning of the cam may of course be adjusted by removal, addition or substitution of shims. The contour of the cam, as indicated in Figures 1 to 4, is such as to maintain line contact with the frusto-conical surfaces of clutch rolls 20, which are tapered to conform to the taper of cam 15, while lines drawn longitudinally along the closest surface portions are parallel, to provide maximum contact with the shank of the stud (30). Viewed from its end the cam includes an enlarged portion, as 19, for each roll, large enough to permit the roll to clear the stud but tapering inwardly circumferentially in a direction opposite to that of normal rotation of the tool until at their closer ends these tapered portions force the rolls closer together than the diameter of the stud.

The clutch rolls 20 are caged in a driven element 25, which is slidable and rotatable within the casing 11—12 and adapted to be clutched thereto by the rolls. A coil spring 22 acts in compression to urge element 25 to the front or left end of the driving casing as viewed in Figs.

1 and 2, and also acts in torsion to tend to turn said element 25 with respect to the driving casing toward such position with respect thereto that the rolls lie in the larger areas 15A of the cam ring. When the parts are so positioned and element 25 is at the forward end of the casing, the rolls are free of the stud or other element to be driven, as indicated above, and the spring is arranged to yieldably urge these parts toward such 10 position. One end of the spring is turned, as at 24, to project into a shoulder formed upon the driven member by reduction of its end to accommodate the spring, while the other end of the spring is similarly turned, as at 26, but projects 15 first radially through a slot 28 in the side of the casing and then longitudinally in such manner that it may lie in any of a plurality of slots, as 31, circumferentially spaced about and near the shank end of the casing. It will be seen that 20 when the spring is so stressed to exert torque that its diameter is decreased, (being also under compression, as stated) the end 26 is held by the spring itself within whichever of the slots 31 it may be located, but that by positively moving such 25 end from one slot to another, the torque exerted by the spring may be regulated.

A socket to receive the studs or other objects to be driven is formed in the element 25 by axially boring the same, as at 35, and into and from 30 such socket the rolls 20 are radially movable. The effective depth of the socket is adjustable by means of a stop screw 33 which closes the rear end thereof and is held in position by means of jam nut 34.

35 Carried by the front end of the casing assembly is an interchangeable nipple 37 upon which is screwed a cap 38. One or more shims, as 39, may be arranged between the cap and the end of the nipple and to enable adjusting the extent 40 to which the cap projects, while larger adjustments may be made by substituting nipples of different lengths.

Concerning the operation of the device, it will be seen that in Figs. 1 and 2 the work into which 45 the stud 30 is to be driven is indicated at 40 in dotted lines. In using the exemplary stud driving device the studs are first positioned in the work by hand, as by turning them into the same to a depth of one or two threads. This is usually 50 done by one workman while another operates the driver, which is ordinarily constantly rotated by the tool in which it is mounted. After slipping the driver over a stud, he bears down against it to force the end of the stud against the stop screw 55 38 and move element 25 inward. During the initial part of the insertion the stud fits freely into the space between the rolls, which are in the larger areas 15A of the cam ring as well as 60 at the larger end of its longitudinal taper, in which position they are yieldably held by the spring 22. Continued forcing of the stud into the driver moves the entire driven element 25 to the rear, or right as viewed in the drawing, with 65 respect to the casing, thereby forcing the rolls into engagement with the outside of the stud under the influence of the cam. As soon as the rolls are forced against the stud, the resistance of the latter tends to cause the rolls to roll upon 70 its surface, and such rolling of the roll members turns the element 25, against the torsional resistance of spring 22, while the rolls are moved toward the smaller portions of the cam along the gradually circumferentially tapered surfaces 75 and so tightly clamped against the outside of

the stud to enable positive driving thereof. (Note Figs. 2 and 4.)

The length of nipple 37 and position of cap 38 are so proportioned to the depth to which the stud is to be driven that the cap strikes the work 5 as the driving is completed, the casing being thereby forced back (to the right) with respect to element 25, and the pressure of cam 15 upon the rolls so relieved. The torque exerted by the spring then becomes effective to turn the element 10 25 and so the rolls with respect to the casing to reestablish these parts in the relation shown in Figs. 1 and 3.

In the modified construction shown in Figs. 6 and 7 analogous portions to those previously 15 described are identified by similar reference numerals with the addition of the distinguishing character "a" to each. The tool shown in these views will be seen to be of a design especially adapted for lighter work, and proportioned to 20 handle relatively long and thin elements although this is a matter serving merely to illustrate the adaptability of the tool to variant work.

Ball clutching elements may be used in place of the rolls 20, as indicated at 20a. They may 25 be arranged and function similarly to rolls 20 previously described, being shown caged in a driven element 25a slidably and rotatable in a casing assembly 11a-12a which also serves as a driving element in like fashion. The cam 15a, 30 also, may in general be similar to cam 15, and inclined both longitudinally and circumferentially to enable forcing the balls 20a against the stud both by axial pressure and by driving torque 35 opposed by the resistance of the stud, while the spring 22a tends to release the balls in both directions.

The adjustable back end 26a of the controlling spring 22a is in this embodiment turned outwardly to enable it to fit in any one of a plurality of slots 31a formed in this instance in and longitudinally of the threaded inner surface of casing section 11a at the socket portion into which the driving shank 10a is screwed. It will be appreciated that the end of the spring is thus locked 45 in place by means of the shank, which must be removed before the tension of the spring may be regulated by moving its end portion 26a to another slot. Accidental disturbance of the spring adjustment is in this fashion positively prevented.

50 Casing section 12a is shown as provided with an elongated integral nipple portion 37a carrying at its end an adjustable abutment cap 38a, the positioning of which is dependent upon the thickness of the shim 39a therebeneath. Major 55 adjustments may of course be made by substituting caps of different dimensions.

It will be seen that no exposed movable parts whatever other than the smoothly rotatable outer casing are employed, and that within the casing, in addition to the rolls, the cage, cam and spring are the only operative elements, despite which great flexibility and adaptability are incorporated.

60 While it will be apparent that the illustrated embodiments of my invention herein disclosed are well calculated to adequately fulfill the objects and advantages primarily stated, it is to be understood that the invention is susceptible 65 to variation, modification and change within the spirit and scope of the subjoined claims.

What I claim is:

1. In a device of the character described, a 70 combined casing and driving element having a 75

substantially cylindrical chamber therein, a driven element within said casing element and limitedly movable both rotatively and longitudinally in said chamber, means yieldably urging 5 one of said elements toward a predetermined longitudinal and angular position with respect to another, said driven element having a work-receiving socket therein accessible from outside through an aligned opening in the casing, clutching means also within the casing and movable into and out 10 of the socket in the driven element, means including a cam carried by said casing and having surfaces inclined circumferentially and outwardly flaring for moving said clutching means into the socket upon movement of the driven element relatively to the casing under the influence 15 of work forced into the socket, said yieldable means comprising a spring acting both torsionally and longitudinally, and secured at one end 20 to the driving element and at the other end to the driven element, and anchoring means for the end of said spring which is secured to the driving element including means for holding said end of the spring in any of various spaced circumferential positions, whereby the torsional 25 effect of said spring may be varied.

2. In a device of the character described, a combined casing and driving element having a substantially cylindrical chamber therein, a driven element within said casing and limitedly 30 movable both rotatably and longitudinally in said chamber, means yieldably urging one of said elements toward a predetermined longitudinal and angular position with respect to another, said driven element having a work-receiving socket 35 therein accessible from the outside through an aligned opening in the casing, clutching means also within the casing and movable into and out of the socket in the driven element, means including a cam carried by said casing and having 40 surfaces inclined circumferentially and outwardly flaring for moving said clutching means into the socket upon movement of the driven element relatively to the casing under the influence of work 45 forced into the socket, said yieldable means comprising a spring action both torsionally and longitudinally, and adjusting means whereby a portion of said spring may be moved, from outside the casing, to any of a plurality of positions.

3. In a device of the character described, a combined casing and driving element having a substantially cylindrical chamber therein, a

driven element within said casing, and limitedly movable both rotatably and longitudinally in said chamber, means yieldably urging one of said elements toward a predetermined longitudinal and angular position with respect to another, said 5 driven element having a work-receiving socket therein accessible from the outside through an aligned opening in the casing, clutching means also within the casing and movable into and out of the socket in the driven element, means including a cam carried by said casing and having surfaces inclined circumferentially and outwardly flaring for moving said clutching means into the socket upon movement of the driven element relatively to the casing under the influence 15 of work forced into the socket, said yieldable means comprising a spring acting both torsionally and longitudinally, and anchoring means including spaced keeper portions for holding an end of the spring against undesired movement, 20 said end of the spring extending through and being accessible and movable from outside the casing.

4. In a device of the character described, a combined casing and driving element having a substantially cylindrical chamber therein, a driven element within said casing and limitedly 25 movable both rotatably and longitudinally in said chamber, means yieldably urging one of said elements toward a predetermined longitudinal and angular position with respect to another, said driven element having a work-receiving socket 30 therein accessible from the outside through an aligned opening in the casing, clutching means also within the casing and movable into and out 35 of the socket in the driven element, means including a cam carried by said casing and having surfaces inclined circumferentially and outwardly flaring for moving said clutching means into the socket upon movement of the driven element 40 relatively to the casing under the influence of work forced into the socket, said yieldable means comprising a spring acting both torsionally and longitudinally, and anchoring means including spaced keeper portions located in one end of the 45 casing for holding a portion of the spring against undesired movement and in any of various positions of adjustment, and a driving shank for the tool, removably affixable to said end of the casing and locking such end of the spring in position 50 when so attached.

CLAUDE I. HESS.
